US0D1083024S

(12) **United States Design Patent** (10) **Patent No.:** **US D1,083,024 S**
(45) **Date of Patent:** **** Jul. 8, 2025**

(54) **REFRIGERATOR FILTER**

- (71) Applicant: **Tianjin Yuanzhi Environmental Technology Co. Ltd.**, Tianjin (CN)
- (72) Inventors: **Kai Zhang**, Tianjin (CN); **Lin Lou**, Tianjin (CN); **Xin Guan**, Tianjin (CN); **Jingguan Du**, Tianjin (CN)
- (73) Assignee: **Tianjin Yuanzhi Environmental Technology Co. Ltd.**, Tianjin (CN)
- (**) Term: **15 Years**
- (21) Appl. No.: **29/923,713**
- (22) Filed: **Dec. 31, 2023**

(30) **Foreign Application Priority Data**

CLAIM

The ornamental design for a refrigerator filter as shown and described.

DESCRIPTION

FIG. 1 is a top-front perspective view of a refrigerator filter. FIG. 2 is a bottom-rear perspective view of the refrigerator filter.

FIG. 3 is a front view of the refrigerator filter.

FIG. 4 is a rear view of the refrigerator filter.

FIG. 5 is a left view of the refrigerator filter.

FIG. 6 is a right view of the refrigerator filter.

FIG. 7 is a top view of the refrigerator filter; and,

FIG. 8 is a bottom view of the refrigerator filter.

1 Claim, 7 Drawing Sheets
